UNITED STATES PATENT OFFICE.

SIDNEY A. KELLER, OF NEW YORK, N. Y., ASSIGNOR TO R. BLACKINGTON & CO., OF NORTH ATTLEBORO, MASSACHUSETTS.

DESIGN FOR A HANDLE FOR SPOONS, FORKS, OR SIMILAR ARTICLES.

SPECIFICATION forming part of Design No. 34,648, dated June 11, 1901.

Application filed May 18, 1901. Serial No. 60,946. Term of patent 7 years.

To all whom it may concern:

Be it known that I, SIDNEY A. KELLER, a citizen of the United States, residing at New York, in the county of New York and State of New York, have invented and produced a new and original Design for the Handle of a Spoon, Fork, or Similar Article, of which the following is a specification, reference being had to the accompanying drawings, forming part thereof.

Figure 1 is a view of the front of the handle, showing my design. The handle is shown connected with the bowl of a spoon, the tines of a fork being indicated in broken lines. Fig. 2 is a view of the back of the handle.

As shown in the drawings, the leading and material feature of my design consists of the curved outlines with which the handle connects with the spoon and the stem connects with the blade at the upper end of the handle, overlaid by conventional thistle-leaves, extending from the margins over the handle in oblique curves, thereby ornamenting the

handle and part of the bowl near the junction of the handle with the sharply-pointed serrations of the thistle-leaves. The representations of the flowering seed-pods of the thistle are interspersed with the leaves, one of which is conspicuous at the end of the blade and the junction of the stem with the blade on the front of the handle. The ornamentations are raised above the surface of the handle.

Having thus described my invention, what I claim as new, and desire to secure by Letters Patent, is—

The design for the handle of a spoon, fork or similar article, as herein shown and described.

In testimony whereof I have signed my name to this specification in the presence of two subscribing witnesses.

SIDNEY A. KELLER.
